UNITED STATES PATENT OFFICE.

JOSEPH J. GESSNER, OF OKMULGEE, OKLAHOMA, ASSIGNOR OF ONE-THIRD TO THOMAS WATERS, ONE-THIRD TO LULA M. GESSNER, AND ONE-THIRD TO JOHN R. SCHEY, ALL OF OKMULGEE, OKLAHOMA.

FURNACE FOR ANNEALING AND FLATTENING GLASS.

Application filed December 6, 1926. Serial No. 153,008.

The object of my present invention is to provide an improved flattening oven within which split cylinders of glass may be more accurately and completely flattened than has heretofore been customary.

The accompanying drawings illustrate diagrammatically my improvement. Fig. 1 is a central vertical section and Fig. 2 a section on line 2—2 of Fig. 1.

In the drawing 10 indicates the main chamber of a flattening oven and lehr 11, a rotary flattening table 12 being mounted in said chamber and provided with a plurality of flattening stones 13.

Communicating with chamber 10 is the annealing tunnel 14 within which are mounted the usual supporting bars 15 and the reciprocating carrying bars 16.

No attempt has been made to illustrate in detail the construction of bars 15 and 16 as they are of common and well-known construction, the bars 16 being interdigitated with the bars 15 and being vertically and horizontally reciprocable in such manner that a sheet of glass placed upon bars 15 may be intermittently raised, forwarded and redeposited on bars 15.

Heretofore the annealing tunnel 14 has connected directly with the chamber 10 at a point closely adjacent the table 12 so that, a sheet of glass having been flattened upon a stone and having been placed upon the receiving ends of bars 15, would be promptly entered into the tunnel 14 when it would be shielded from the heat of chamber 10.

My present invention differs from previous constructions in that I form, between chamber 10 and the entrance end of tunnel 14, a supplemental heating chamber 17 which I call a settling chamber. This chamber 17 is most conveniently a lateral extension of chamber 10 so that the heat in chamber 10 may freely circulate in the settling chamber 17. I also provide supplemental burners 18 by means of which proper heating conditions may be established in settling chamber 17.

Chamber 17 is of such dimensions, lengthwise of the carrying rods, that a sufficient time will elapse between the time when a freshly flattened sheet has been placed upon the receiving ends of bars 15 and the time when said sheet, in normal operation, will have been projected into the receiving end of tunnel 14, that said sheet, being softened

by the heat maintained in chamber 17, may 55 settle flatly upon the bars 15 and 16.

In order to insure proper heat conditions within the tunnel, so that the sheets of glass may at first be sufficiently weakened to permit gravity to thoroughly flatten the sheets 60 and so that the sheets may gradually cool and be thoroughly annealed, I arrange in the tunnel below rods 15 a plurality of transverse partitions 20 so that the tunnel is divided into a series of compartments or chambers 21, the heat condition of each of which may be independently determined by proper regulation of one or more burners 22 arranged in each chamber. Each of said chambers is provided at its bottom with 70 doored ventilating openings 23. Other valved ventilating openings 24 in the upper region of the tunnel are provided so that the heat conditions in any one of the compartments 21 may be regulated and accurately determined.

Partitions 20 are spaced apart the forwarding distance of bars 16 so that each sheet of glass passes successively into and through each chamber 21. Proper regulation of the burners and dampers of each chamber 21 makes possible an accurate application of heat to each sheet of glass so that it will emerge from the tunnel properly flat and annealed.

I claim as my invention:

1. A flattening oven for window glass comprising a main flattening chamber, an annealing tunnel, a settling chamber forming a connection between the flattening chamber and the receiving end of the tunnel, and in unobstructed communication therewith whereby a flattening temperature will be maintained therein from the heat in the flattening chamber, and means for receiving and forwarding successive sheets of glass from the main chamber through the settling chamber and into and through the tunnel.

2. A flattening oven for window glass comprising a main flattening chamber, an annealing tunnel divided into a plurality of successive compartments, heating means for independently controlling the heat conditions of each compartment, a settling chamber forming a connection between the flattening chamber and the receiving end of the tunnel, and in unobstructed communication

therewith whereby a flattening temperature will be maintained therein from the heat in the flattening chamber, and means for receiving and forwarding successive sheets of glass from the main chamber through the settling chamber and into and through the tunnel by successive steps from one tunnel chamber to another.

3. A flattening oven for window glass comprising a main flattening chamber, an annealing tunnel divided into a plurality of successive compartments, means for independently controlling the heat conditions of each compartment, a settling chamber forming a connection between the flattening chamber and the receiving end of the tunnel, and in unobstructed communication therewith whereby a flattening temperature will be maintained therein by the heat in the flattening chamber, means independent of the heating means for the tunnel for modifying the heat condition of said settling chamber, and means for receiving and forwarding successive sheets of glass from the main chamber through the settling chamber and into and through the tunnel by successive steps from one tunnel chamber to another.

4. A flattening oven for window glass comprising a main flattening chamber, an annealing tunnel divided into a plurality of successive compartments, heating means for independently controlling the heat conditions of each compartment, a settling cham-

ber forming a connection between the flattening chamber and the receiving end of the tunnel, and in unobstructed communication therewith whereby a flattening temperature will be maintained therein by the heat in the flattening chamber, means independent of the heating means for the tunnel for modifying the heat condition of said settling chamber, and means for receiving and forwarding successive sheets of glass from the main chamber through the settling chamber and into and through the tunnel by successive steps from one tunnel chamber to another.

5. A flattening oven comprising a main flattening chamber, a settling chamber freely open to the heat of the main chamber whereby a flattening heat will be maintained in the settling chamber by the heat in the flattening chamber, an annealing tunnel communicating with the settling chamber at a point remote from the main chamber, and means extending from the main chamber through the settling chamber and tunnel upon which successive sheets of glass may be received in the main chamber and forwarded first into and through the settling chamber and thence into and through the tunnel.

In witness whereof, I have hereunto set my hand at Okmulgee, Oklahoma, this 15th day of November, A. D. one thousand nine hundred and twenty six.

JOSEPH J. GEESNER.
